UNITED STATES PATENT OFFICE.

WILLIAM D. MOUNT, OF SALTVILLE, VIRGINIA, ASSIGNOR TO NITROGEN PRODUCTS COMPANY, OF PROVIDENCE, RHODE ISLAND, A CORPORATION OF RHODE ISLAND.

PROCESS OF PRODUCING CYANID.

1,329,722.

Specification of Letters Patent.

Patented Feb. 3, 1920.

Original application filed April 26, 1918, Serial No. 230,876. Divided and this application filed October 4, 1918. Serial No. 257,314.

To all whom it may concern:

Be it known that I, WILLIAM D. MOUNT, a citizen of the United States, residing at Saltville, in the county of Smyth and State 5 of Virginia, have invented certain new and useful Improvements in Processes of Producing Cyanid, of which the following is a specification.

This invention relates to a process for fixing 10 nitrogen, more especially through the intermediacy of solid or semi-solid reaction materials which are caused to feed through a preferably continuously operating retort, while free nitrogen is caused to react upon 15 said materials to effect the fixation of said nitrogen.

One of the objects of said invention is to induce a regulated flow of reaction materials through a retort or the like to the end 20 that proper reaction conditions may be maintained in said retort; so that the process, as a whole, may be effectuated in a better manner than was found possible previous to the development of the present process 25 and the apparatus whereby it may be effectuated.

These and other objects of my invention will be hereinafter referred to and the novel 30 combinations of steps and features of my process, whereby said objects may be attained will be more particularly pointed out in the appended claims.

In one of its aspects my invention concerns an improvement upon the apparatus 35 shown in the patent to John E. Bucher, No. 1,120,682, dated December 15, 1914, in which a furnace is shown, through a retort in which a column of briquetted material is fed by gravity while a current of nitrogen or 40 nitrogenous gas is caused to ascend the column, successively cooling the briquets which have traversed the reaction zone, the nitrogen being pre-heated in so doing,—and then passing through or into the highly heated 45 portion of the retort to react with carbonaceous material and sodium carbonate or the like in the charge, to form, for example, sodium cyanid.

In operating furnaces of this description, 50 however, considerable difficulty has been en-

countered in removing the cyanized material from the retort, owing to the binding property of the cyanid formed.

The charge while passing through the heat zone of the apparatus acquires a high 55 content of cyanid, and when the cyanized mass passes into the cooling zone below, the cyanid hardens, with the result that the charge, initially supplied in pieces or preferably in the form of briquets, is united into 60 a fairly solid column; the cyanid acting as a binder to unite the briquets wherever they make contact with each other.

This column is, of course, filled with interstices when the operation is properly 65 conducted; and the passage of nitrogen up therethrough is hence not materially hindered.

It is sufficiently rigid and strong, however, to offer a problem as how best to disintegrate it without too severely jarring the 70 retort, since heavy continuous vibration obviously tends to shorten the life of the apparatus.

It is also desirable not to unnecessarily 75 pulverize the cyanized material on account of objection to such powder during subsequent operations. The apparatus shown in the drawings fulfills these requirements and enables the effectuation of the herein described process in a particularly desirable 80 way. These drawings will, accordingly, now be considered in some detail.

In said drawings which form parts hereof and in which like reference characters designate like parts in the respective views, I have shown a preferred embodiment of my invention; but as I am aware of various changes and modifications which may be made herein and in the process effectuated 90 in such an apparatus, without departing from the spirit of said invention, I desire to be limited only by the scope of the claims, broadly interpreted in the light of my disclosure. 95

Referring to the drawings:

Figure 1 is a side elevation of my improved cyanizing apparatus; said elevation being partly broken away to show details of construction. 100

Fig. 2 is a rear view of the lower part of said apparatus; the view being taken from the line II—II of Fig. 1.

Fig. 3 is a detail section taken on the line 5 III—III of Fig. 1; and

Fig. 4 is a detail section taken on the line IV—IV of Fig. 1.

The apparatus preferably comprises a retort 1, of iron or other suitable material, 10 which projects up through the furnace brick-work 2, and similarly extends down through the bottom plate 3; the preferably enlarged lower end 1' of said retort being seated in the mouth of the feed-table casing 4.

A gas-tight seal at the lower end of the retort is formed by compressing a packing of kieselguhr or other suitable material 5 around the outer wall of said retort, by 20 means of an annular casting 6.

The preferably continuously moving charge 7, is fed into the hopper 8, and portion after portion thereof drops gradually and successively down through the pre-heating section of the retort until it enters the reaction zone within the heated chamber 9; after which it is cooled somewhat in the enlarged section 1', before entering the casing 4.

30 The chemistry of the reaction need not be here further considered other than to state that in the preferred methods of conducting the operation, the charge is composed of briquets, the ingredients of which may be, 35 for example, sodium carbonate, pulverized coke, charcoal, or the like and finely divided iron. Nitrogen is supplied to this charge in the manner hereinafter described, so that at a temperature of, say 1000° C., the carbon 40 of the coke or charcoal is caused to unite with the free nitrogen and with sodium supplied by the sodium carbonate, to form cyanide. This reaction is preferably effected catalytically through the intermediacy of the iron, and by the time that a given 45 briquet arrives at the bottom of the heat zone, it is normally highly cyanized.

During their progress through the heat zone, the cyanide present in the briquets is 50 normally molten, in large part, but as the cyanized material enters the cooling section 1', its fluid content commences to congeal; with the result that by the time such material enters the casing 4, it has set into a quite rigid column.

A rotary table 10 in this casing supports said column, and is provided with means for nipping or breaking off briquets or fragments thereof from the bottom of the column 60 to enable the charge in the retort to gradually descend.

The preferred device for this purpose, is a star 11, having three points or arms and provided with pyramidal teeth 11'. Said star is loosely pivoted upon the upper sur-

face of table 10, with its axis of rotation 12 eccentric to that of the table, as shown in Fig. 3, wherein the location of the shaft 13 which supports said table is indicated by a dotted circle.

70 Shaft 13 is suitably journaled in bushings 15—15' disposed respectively in the base member or plate 14 and its yoke 16; the table shaft being driven by a worm wheel 17, which in turn is driven by a worm 18 mounted on a shaft 19 which is preferably caused to revolve step by step by means of a ratchet wheel 20 and pawl 21. Wheel 20 is of course secured to the shaft 19 and the pawl 21 is carried on an arm 22, pivoted on 80 shaft 19, in a known fashion.

The shaft 19 is journaled in the yoke 16 and in a bearing 23 attached to one side of the hopper 24, which may conveniently be made a part of the base plate 14.

85 The hopper 24 receives the fragments nipped off or detached from the charge, and delivers them to a cooling tank 25. This tank is preferably, what may be termed, "flat"—being quite narrow in proportion 90 to its breadth and depth, as shown in Figs. 1 and 2; so that it affords a very extensive surface, in proportion to its volume or cubical content, to permit of air or water cooling and cooling by radiation.

95 It may be here noted that the material to be cooled is a relatively poor conductor of heat; but by thus providing a large "flat" tank, the distance from the most interiorly disposed point in the mass to be cooled, to 100 the exposed cooling surface need not be over two or three inches. The tank is also preferably tapered toward the bottom, as shown, to still further reduce said distance, with the result, that the temperature of the material drawn from valve 26 at the lower end of said tank is normally but very little 105 above that of the surrounding atmosphere.

In the construction given by way of illustration, a bearing bracket 27 is mounted 110 upon one side of the tank, and has journaled therein a shaft 28, one end of which carries an eccentric 29, and the other end a sprocket wheel 30 or the like. A rod 31 connects the eccentric strap 29' with the 115 arm 22, so that as the shaft 28 is rotated by the wheel 30, rod 31 oscillates the arm 22, to cause the pawl 21 to step the ratchet wheel around whereby to cause a corresponding step by step but much slower rotary motion of the feed table.

120 As this action takes place, on account of the eccentricity of the star 11 with respect to said table, the teeth 11' are caused to powerfully nip off fragments from the column above the table; first one tooth coming into play and then another, or, at times, possibly two of the teeth, simultaneously breaking off fragments.

125 A further advantage in thus eccentrically 130

mounting a loosely pivoted toothed element upon the rotary table, is that the charge is prevented from idly rotating in its retort; as it is apt to do where the table itself carries the teeth and has its axis coincident with that of a cylindrical retort.

The tank preferably has a capacity two or three times that of the retort, when air cooled as shown.

10 Air is excluded from the tank and of course from the casing 4 and retort, to prevent the oxidation of the cyanid formed, to cyanate; and for this and other reasons hereinafter noted, nitrogen is introduced into 15 the bottom of the tank through a pipe 32; the flow of gas being controlled by means of valve 33.

The nitrogen current flows up through the tank, between the interstices of the briquets 20 or charge fragments, aiding in cooling said fragments and in turn being preheated by contact with them.

By the time that it enters the casing 4 and passes thence through the laterally unsupported walls of the rigid briquet column, into retort section 1', it is quite hot; but still of course below the melting point of cyanid. As it thereafter traverses the pores and interstices of the briquetted charge, it 30 is gradually raised to the reaction temperature, while again in turn aiding in cooling the descending cyanized charge, to cause any liquid present in the latter to congeal or solidify.

35 The valve 26 at the lower end of the cooling receptacle, is preferably a one-way cock, as shown in Fig. 4; having therein a pocket 26' so that when it is, for example, continuously rotated, this pocket is alternately filled and emptied at every revolution.

40 Preferably this valve is driven slowly by means of a sprocket and chain drive; shaft 19 having feathered on one end a clutch 34 which when operatively disposed causes said 45 shaft to drive a sprocket wheel 35, which in turn actuates a chain 36 to drive a sprocket wheel 37 mounted on a trunnion 38 of said valve 26. Normally, of course, before the clutch is thrown to cause valve 26 to rotate, 50 a receiving can 39 is placed in position below the valve casing 40.

The general operation of the apparatus may now be briefly reviewed.

Assuming that the retort is charged with 55 briquets and that its heat-zone section has attained the proper temperature, the supply of heating being maintained by the flow of hot gases through the furnace in the direction of the arrows; the charge will then 60 gradually move down through the retort, each briquet being first-preheated by the ascending gaseous reaction products.

Thereafter each briquet will, in turn, be 65 cyanized and then pass into the cooling section 1', where its liquid content will con-

geal. In so doing the briquets in said section will adhere together to form a rather rigid structure, which will be sustained by the rotating table and will in turn sustain the remainder of the charge in the retort. 70 The laterally self-sustaining character of this briquet structure permits the nitrogen flowing through the casing 4, to gain free access to the interior of the column, from all sides of the latter and thence up to the re- 75 action zone.

The rotation of the table causes the teeth and other abrading parts of the eccentrically pivoted star or cutter to bite off pieces from the bottom of the column, and these loose 80 fragments are gradually worked off the table and fall through the hopper 24 into the cooling tank; there being no lateral supports around the lower end of the column to hinder this movement. Pulverization of 85 the briquet material should preferably be avoided to favor the subsequent recovery of the cyanogen compound by an extracting operation.

Nitrogen supplied from pipe 32, cools the 90 briquets in the cooling tank and thereafter lowers the temperature of those in the casing 4 and retort section 1'; the nitrogen being preheated thereby.

Meanwhile the charge in the retort is renewed so as to maintain said retort substantially full; and if the reaction gases be not collected as they emerge from the hopper 8, they will burn at this point. 95

It has been found most convenient and 100 practicable, however, to make no attempt to recover these gases; the hopper 8 being left open to permit of the free introduction of the charge.

The substantially cold briquets in the 105 lower end of the tank are withdrawn, from time to time or continuously, as desired, and especially in the latter mode of operation, is it desirable to provide some means, such as the valve 26 and its associated parts, to prevent wastage of the nitrogen supplied to the retort; or, even worse, such an outflow of both cooled briquets and nitrogen from the receptacle 25, as might tend to create a 110 backward flow of nitrogen not only through the cooling tank, but even downwardly through the retort; since in such case free atmospheric oxygen would also flow down from the open upper end of said retort. 115

I may add, that I have found it advanta- 120 geous to thus supply nitrogen to the bottom of the cooling receptacle, in order to more efficiently and economically cool the briquets while at the same time conserving much of the heat of which they are deprived. 125

In conclusion, I desire to point out that the herein described method is, in certain of its aspects, especially concerned with the turning to advantage in several ways, of what otherwise would tend to give rise to 130

4
considerable trouble in effecting the desired fixation of nitrogen. I refer here more particularly to the chilling and congealing of the cyanid formed, following its removal 5 from the heat zone, which congelation, as above noted, has been favored in controlled conditions and utilized to aid in the subsequent preparation of the cyanized material for the extracting operation.

10 The disclosure made herein was originally presented in my application for United States Letters Patent, Serial Number 230,876, entitled Cyanid producing apparatus and filed April 26, 1918; the present case 15 being a division of said parent application.

Having thus described my invention, what I claim is:

1. The method of effecting a reaction between a material in the gaseous phase and 20 material a part at least of which is in the solid phase, which comprises so disposing the last mentioned material as to provide interstices through a mass thereof, supplying heat to said mass from a source of the same, flowing said material in the gaseous phase through said interstices to combine a portion thereof with material in said mass 25 to form a compound which tends to liquefy at the temperature to which said mass is heated, causing a movement of said mass with said compound therein, away from the source of heat, while cooling said mass sufficiently to cause said compound to congeal 30

and bind the mass in which it is present into a substantially rigid structure, reducing 35 said structure to fragments, collecting said fragments, and cooling them to a temperature at which said compound is substantially inoxidizable by passing relatively cold nitrogen through the mass of collected 40 fragments.

2. The method of fixing nitrogen which comprises, reacting with free nitrogen upon a hot briquetted mass containing sodium carbonate and carbon, to form a cyanogen compound, cooling said mass to congeal said compound therein, whereby to bind said mass into a rigid porous structure capable, when displaced from the place where it is formed, of maintaining its shape when laterally unsupported, displacing said structure to expose a laterally unsupported columnar section at the base thereof and to favor the solidification of further quantities of said compound, and supplying free 55 nitrogen for the continuance of the reaction aforesaid, by introducing said nitrogen into said laterally unsupported columnar section for movement through the pores of the latter up toward the heated reaction zone. 60

In testimony whereof I have affixed my signature in the presence of two witnesses.

WILLIAM D. MOUNT.
